BOOM ANGLE INDICATOR FOR CRANES

Carl M. Cooper, Compton, Calif., assignor of forty percent to S. Fishfader, Los Angeles, Calif.

Application October 25, 1954, Serial No. 464,233

3 Claims. (Cl. 340—282)

This invention relates to a device whereby the angle or position of the boom of a crane will be indicated to the operator of the crane, this indicator being within the cab so that the operator will at all times be apprised of the exact position of the crane boom.

An object of my invention is to provide a boom position indicator for cranes in which the pendulum on the boom actuates a potentiometer, the potentiometer being wired to an ammeter or voltmeter situated in the cab of the crane.

Another object of my invention is to provide a novel boom indicator for cranes, in which the ammeter or voltmeter is also connected to a mercury switch which indicates the tilt or angle of the cab to serve as a warning if the cab or crane is tilting to a dangerous degree, due to an excessive load on the boom.

Another object of my invention is to provide a novel boom angle indicator of the character stated, in which the pendulum is mounted within a housing and is damped in a suitable liquid to prevent excessive oscillation of the pendulum.

Other objects, advantages and features of invention may appear from the accompanying drawing, the subjoined detailed description and the appended claims.

In the drawing:

Figure 1 is a side elevation of a crane with my boom indicating mechanism mounted thereon.

Figure 2 is a wiring diagram of my boom indicator.

Figure 3 is a side elevation of the boom angle indicator.

Figure 4 is a front elevation of the same with the cover plate removed.

Figure 5 is a sectional view taken on line 5—5 of Figure 4.

Referring more particularly to the drawing, the numeral 1 indicates the cab of a crane and 2 the boom of that crane. In a boom type crane, particularly those of the portable types, it is possible to tip the crane over by attempting to lift too great a load, or if the boom is at an incorrect angle a lesser load on the boom will also tip the crane, and for these reasons it is desirable that the operator be apprised of the exact angle of the boom without having to observe the boom visually and estimate the angle and whether that angle is safe. With my invention a visual means is provided within the cab 1 of the crane so that the operator can observe a finger or needle of an instrument, this needle indicating in degrees the angle of the boom. A housing 3, preferably cylindrical in shape, is mounted on the boom 2 by means of an arm 4, which projects downwardly from the housing and is fixedly attached to a C-clamp 5. The C-clamp 5 attaches to a suitable member of the boom 2. A horizontal shaft 6 is journaled in the housing 3 and projects into the tube 7, projecting from the rear of the housing 3. A resistance or potentiometer 8 is mounted within the tube 7 and a finger 9 on the shaft 6 moves over the potentiometer as the shaft 6 is rotated. A pendulum 10 is suspended from the shaft 6 and is positioned within the housing 3. It will be evident that as the boom 2 moves upwardly

2

and downwardly in an arc, that the pendulum 10 will move within the housing 3, thus rotating the shaft 6 and thereby moving the contact finger 9 over the potentiometer 8. The movement of the pendulum 10 is damped by the liquid 11 which partly fills the housing 3. The housing 3 and the pendulum 10 therein, can be so positioned on the arm 2 that the finger 9 will be at the zero position of the potentiometer 8 when the boom 2 is in its extreme raised position. As the boom 2 is lowered, the finger 9 will move over the potentiometer 8, thus varying the resistance in the electrical circuit, to be further described, and actuating a voltmeter or ammeter, the needle of which moves over a chart calibrated in degrees. The voltmeter 12 is mounted in the cab 1 of the crane and is so positioned that the operator can easily see the dial 13 which is calibrated in degrees, as previously stated. The finger 14 of the voltmeter moves over the dial 13, as will be evident, depending upon the position of the finger 9 on the potentiometer 8.

20 The wiring diagram is as follows: A source of power, preferably a battery 15, supplies power to the leads 16 and 17 extending therefrom. A switch 18 may be included in the circuit, if desired. The lead 16 extends to one end of the potentiometer 8 and the lead 17 extends to the other end of that potentiometer. A push button switch 19 has contacts 20 and 21 and the contact 20 is connected by lead 22 to the shaft 6, or to the finger 9 which sweeps the potentiometer 8. The contact 21 is connected by lead 23 to a rheostat 24. This rheostat is the usual adjusting rheostat of a voltmeter whereby the hand 14 can be adjusted to a zero position. A second set of contacts 25—26 of the switch 19 are connected as follows: The contact 25 is connected to the lead 17. Similarly, the contact 26 is connected to the lead 23, as shown. Thus in one position the switch 19 engages the contacts 20—21, and in this position the potentiometer 8 through the position of the finger 9 thereof will actuate the voltmeter 12, causing the hand 14 thereof to move to a position corresponding to the position of the finger 9, but since the dial 13 is calibrated in degrees the operator will be able to read the angle of the boom 2 in degrees and determine if that angle is safe or unsafe. When the switch 19 engages the contacts 25—26, current flows to the rheostat 24 for the purpose of adjusting the hand 14 of the voltmeter in the usual manner. A mercury switch 27 includes several contacts 28, 29 and 30. The drop of mercury in the switch will move to engage these contacts as the switch is tilted. The switch 27 is mounted either upon or adjacent to the voltmeter 12 and thus as the cab 1 might tilt the switch 27 would be actuated to give a warning. The contact 28 of the switch 27 is connected to the lead 16 by the wire 31. A buzzer 32, or other audible warning, is connected by lead 33 to the contact 29; the other side of the buzzer being connected by lead 34 to the main line 17. A warning light 35 may also be included in the circuit and this light is connected by lead 36 to the lead 31 and the contact 30, and by the lead 37 to one end of the potentiometer 8 or to the lead 17, which in this instance is the same thing.

65 In operation as the boom 2 raises and lowers on its pivot the pendulum 10 will swing in the housing 3, thus moving the finger 9 over the potentiometer 8. The voltage supplied to the voltmeter 12 is thus varied, causing the hand 14 of the voltmeter to move over the dial 13, indicating in degrees the position of the boom 2. Any excessive tilting of the cab 1 of the crane causes the mercury switch 27 to engage contacts 29 or 30, thus actuating the buzzer 32 or the light 35. The pendulum 10 is prevented from violently swinging back and forth within the housing 3 by the liquid (such as oil) within the housing and in which the pendulum moves.

Having described my invention, I claim:

1. A boom angle indicator for cranes comprising a housing, attaching means on the housing to secure said housing to the boom, a pendulum pivotally mounted in the housing, a variable resistance, means operable by the pendulum to vary the resistance, a galvanometer, and electrical leads extending from said resistance to the galvanometer, said galvanometer being calibrated in degrees, a tilt switch mounted adjacent the galvanometer, a warning means, and electrical leads extending from the tilt switch to the warning means.

2. A boom angle indicator for cranes comprising a housing, attaching means on the housing to secure said housing to the boom, a shaft extending into the housing, a pendulum mounted on the shaft and positioned within the housing, a variable resistance mounted on the housing, said shaft extending to the variable resistance, a finger on the shaft adapted to sweep over the variable resistance, a galvanometer, and electrical leads extending from said resistance to the galvanometer, said galvanometer being calibrated in degrees, a tilt switch mounted adjacent the galvanometer to indicate excessive tilting of said galvanometer, a warning means, and electrical leads extending from the tilt switch to the warning means.

3. A boom angle indicator for cranes comprising a 25

housing, attaching means on the housing to secure said housing to the boom, a shaft extending into the housing, a pendulum mounted on the shaft and positioned within the housing, a damping liquid in the housing in which the pendulum is immersed, a variable resistance mounted on the housing, said shaft extending to the variable resistance, a finger on the shaft adapted to sweep over the variable resistance, a galvanometer, and electrical leads extending from said resistance to the galvanometer, said galvanometer being calibrated in degrees, a tilt switch mounted adjacent the galvanometer to indicate excessive tilting of said galvanometer, a warning means, and electrical leads extending from the tilt switch to the warning means.
